Primary Examiner — Messina L Smith*Assistant Examiner* — Kaitlyn G Wiltshire(74) *Attorney, Agent, or Firm* — Lippes Mathias LLP(57) **CLAIM**

The ornamental design for a high flow ember shield as shown and described.

DESCRIPTION

FIG. 1 is a front perspective view of a high flow ember shield showing my new design;

FIG. 2 is a bottom perspective view thereof;

FIG. 3 is a front view thereof;

FIG. 4 is a bottom view thereof;

FIG. 5 is a left side view thereof;

FIG. 6 is right side view thereof;

FIG. 7 is top side view thereof; and,

FIG. 8 is bottom side view thereof.

The broken lines in the figures depict portions of the high flow ember shield that form no part of the claimed design.
